Inventor,
Jacob Riffkin
G. M. Shulman
Atty.

UNITED STATES PATENT OFFICE.

JACOB RIFKIN, OF WILKES-BARRE, PENNSYLVANIA.

UNION GARMENT.

Application filed August 10, 1925. Serial No. 49,308.

This invention, which relates to a union garment, embodies improvements on the union garment set forth and claimed in my Patent No. 1,386,950, dated August 9, 1921.

5 In the union garment set forth in my aforesaid patent, the "split" or vent is arranged along the top of each shoulder part of the garment and the fastenings are disposed in the same position. Consequently, 10 when an object or weight is carried on either shoulder, the pressure of the fasteners on the shoulder bones results in pain and discomfort to the wearer of the garment.

The arrangement of the vent as set forth 15 in my patent does not conduce to flat and smooth arrangement of the reinforcing strips but, on the contrary, the vent has a ruffled or puckered appearance. Aside from this, the fasteners are exposed and the appearance is 20 not as neat as it might be.

I have also found that with the vent or "split" arranged on the tops of the shoulders, there is a tendency for the garment to accidentally pull open or apart, particularly 25 when any object is carried on the shoulder.

My object is to provide improvements by 30 which the foregoing defects are eliminated and to provide the vent or "split" at the front, instead of at the top, of the shoulder part of the garment; to conceal the intermediate fastener for the vent; to so construct and arrange the vent that it will 35 neither ruffle, pucker, gap, nor pull open accidentally when an object is carried on the shoulder, or at other times, and whereby carrying of an object on the shoulder will not result in pain or discomfort to the wearer because the vent and the fasteners will be disposed so that the object will not rest on 40 them.

In the union garment of my patent, opening of the vents, is accomplished by a general sideward pull, that is, to the left and right respectively, which is not the natural 45 motion of the hand and arm that should be exercised for the purpose. To enable the vent to be quickly and conveniently opened by a forward and downward pull, is another reason why the vent embodying the 50 present invention has been located at the front of the shoulder, instead of along the top thereof and, for the further reason, that with the vent arranged as set forth herein- 55 after, it may be more conveniently buttoned or fastened than when it is arranged on top of the shoulder.

Furthermore, the present improvements provide for more easy and convenient stepping into the garment or its removal than when the vents are on the shoulders. 60

A practical embodiment of the invention is described hereinafter and is disclosed in the accompanying drawings, in which—

Figure 1 is a front view of a union garment provided with the present improvements, the vents being closed, showing the appearance when the garment is worn; and 65

Fig. 2 is a front view showing the vents open and the front of the garment spread out to permit the user to step into it. 70

The construction of the garment being substantially that disclosed in my Patent 1,386,950, except those parts, previously set forth, which relate to the new arrangement, position, and manner of fastening the vents, 75 only a brief description of the old parts of the garment is necessary.

The garment is of the class embodying a connected blouse and legs or pants parts, particularly overalls. The legs or pants appear at 1, the back is shown at 2, the blouse at 3 and the sleeves appear at 4. 80

The garment is split from its neck to its crotch at 5 and provided with any suitable fastenings such as 6 therefor, as usual in 85 garments of this kind.

Whereas the vents of the garment of my Patent 1,386,950 are located on the tops of the shoulders or shoulder parts, and therefore subject to the disadvantages which have been heretofore set forth, in the present garment there is no seam or reinforcement of any kind on the tops of the shoulder parts and the vents are located well down and at the fronts of the shoulder parts. This 90 change of position entirely eliminates discomfort, chafing and pain on the shoulder bones of the wearer when any object of appreciable weight is being carried on either or both shoulders. 95

The reinforcements for the vents are substantially the same as to seams and stitching as disclosed in my aforesaid patent and specific description thereof is unnecessary. 100

The vents 7 extend from the neck band 8 105 downwardly, in a curved shape and general diagonal arrangement to points or locations 9 which reach nearly to the stitching 10 which connects the sleeve to the blouse 3. The vents 7 are located well down from the 110 crests of the shoulders and at the front of the garment. The neck band 8 does not ter-

minate at the front in line with the crests of the shoulder part of the garment but its ends are extended somewhat forwardly and they are provided with parts 11 of suitable fastenings, for instance snap fastenings.

The reinforcements 12 for the underlying parts of the vents are entirely at the fronts of the shoulders, as previously described and they are provided with parts 13 of suitable fastenings, for instance snap fastenings.

The reinforcements 14 for the overlying upper front parts of the garment are provided on their inner faces with parts 15 of fastenings adapted to engage the fastenings 13. The parts 15 are wholly concealed by the overlying parts, thus rendering the garment neater in appearance in the region of the vents and making it appear that there are no vents or splits at the fronts of the shoulder parts.

The overlying front parts of the garment have supplemental neck bands 16 provided with fastenings, for instance parts of snap fastenings 17 adapted to engage the fastenings 11. The supplemental neck bands 16 are finished by providing them with turnover or fold-over collar sections 18 which greatly add to the neat appearance of the garment.

When in use the garment appears as in Fig. 1. When it is to be put on or taken off, the fastenings are disconnected from each other and the front or overlying upper parts of the garment are pulled downwardly by a natural hand and arm movement to spread them apart as shown in Fig. 2, whereupon there is afforded a large opening, extending nearly to the arm pits of the garment, enabling the latter to be easily put on or taken off when opened as shown in Fig. 2.

What I claim is:

A union outer garment or overalls comprising a blouse and leg or pants parts, the blouse having an open front from its neck downwardly and provided with suitable fastening means therefor, and being provided forward of its shoulder parts below the crests of said shoulder parts with vents extending downwardly in general diagonal arrangement from the neck to the general region of the junction of the sleeves with the blouse below the crests of the shoulder parts, the blouse and the shoulder parts being provided with overlapping parts at the vents, and means for fastening the overlapping parts together.

In testimony whereof I affix my signature.

JACOB RIFKIN.
